UNITED STATES PATENT OFFICE.

ANDREAS OTT, OF OBERKASSEL-SIEGKREIS, GERMANY.

STEREOTYPE-MATRIX MACHINE.

1,169,279.

Specification of Letters Patent.

Patented Jan. 25, 1916.

Application filed November 15, 1913. Serial No. 801,239.

To all whom it may concern:

Be it known that I, ANDREAS OTT, a subject of the Emperor of Germany, residing at Oberkassel-Siegkreis, Germany, have invented a certain Stereotype-Matrix Machine, of which the following is a specification.

The present invention relates to a machine in which stereotype matrices are made by means of a type wheel which is operated through the medium of key-levers and which works against a platen carried by a sliding carriage.

The invention consists in the first place in the provision of a carriage feeding mechanism which can be set for any desired spacing of the letters and characters. In the second place an electromagnet with adjustable core is provided which operates the type wheel and which is energized by the depression of the key-levers. Several improvements are also introduced in connection with the carriage, the platen, and the guide for the matrix material.

In the accompanying drawings the invention is illustrated, Figure 1 representing a side view of the machine, in section on the line A--A of Fig. 2, and Fig. 2, a plan of the machine, the carriage being omitted for the sake of clearness.

A machine frame 1 contains a guide-way 3 for the carriage 4 which has at each end a bracket 5 for the reception of the shafts of the platen 6 and two guide-rollers 7 and 8. The carriage holds a trough 10 for moistening the matrix-material 9 which is guided by a roller 11 through the liquid and then led to the rollers 7 and 8. To the underside of the carriage a toothed rack 12 is secured which normally meshes with a worm 13 for feeding the carriage. The shaft of the worm 13 is rotatably held at one end in a U-shaped shackle 19 whose ends are so connected to a shaft 15 that it can turn about the latter. The free end of the worm shaft is guided vertically between two brackets 22 and is supported on a wedge 23 which is slidably arranged in slots made in said brackets. A bell-crank lever 24, having an operating knob 25, has one arm pivoted to the wedge 23 for sliding the latter longitudinally within the brackets. As the wedge is moved in the direction of its thicker end, it causes the supported end of the worm shaft to descend so as to disengage the worm from the rack 12 and allow the carriage to be moved freely.

The worm is driven by a bevel gear 21

which is secured to the shaft 15 between the members of the shackle 19 and which meshes with a bevel gear 20 connected to the worm shaft. The shaft 15 is held in bearings 16 and receives its motion from either of a plurality of shafts 14 which are held at right angles to the same in bearing arms 2 connected to the frame 1. Bevel gears 17 on the shafts 14 mesh with corresponding gears 18 mounted on the shaft 15. For operating the shafts 14 a plurality of double-armed key-levers 27 with keys 26 is provided. These levers turn about a shaft 28 and are controlled by springs 29 and abutments 30 and 31. Each key-lever has on one of the shafts 14 a ratchet wheel 34 which it operates by means of two spring pawls 32 and 33. The pawl 32 turns the wheel when the lever is depressed, and the pawl 33, which is provided with a hooked end, engages and turns the wheel when the lever is restored by the spring 29 to its normal position. The rotation of the wheels 34 is transmitted by the shafts 14 and 15 to the worm 13 for feeding the carriage. The pawls are supported by screws 35 which can be adjusted separately for holding the pawls in engagement with the wheels during a greater or less part of the lever movement, thereby causing the wheels to be turned to a greater or less number of tooth spaces. In this manner the feeding of the carriage can be varied at will for each key separately and for each period of its movement.

The embossing of the matrices is effected by means of a type wheel 36 which is connected to the key-levers so as to be adjusted by the latter about its axis into a different position for each lever. The mechanism employed for this purpose is well known and is, since it forms no part of the invention, left out of the drawings to show the other parts more clearly.

The platen 6 is provided with a plane surface against which the embossing by means of the type wheel 36 is done. For holding the matrix material in position on the platen, a flexible steel sheet 37 is connected to the carriage 4 and bears against the material 9 by means of rollers 38. A slot is made in the sheet 37 to admit the type wheel 36 to the platen.

The application of the type wheel 36 to the matrix material is effected by means of an electromagnet 43 at each depression of a key-lever. The magnet 43 is mounted on

a bracket 42 which also holds, on a pivot 41, the arm 39 to which the type wheel 36 is connected. A spring 45 tends to hold the type wheel away from the platen 6. The arm 39 has a rearward extension 40 which forms an armature for the core 44 of the magnet 43. The electric circuit of the magnet 43 is closed by means of the key-levers 27 each one of which carries for this purpose a contact piece 50 adapted, at the depression of the lever, to abut against and connect electrically a pair of studs 50. One stud of each pair is connected to a bar 46 and the other to a bar 47. These bars are insulated and supported by springs 48 on brackets 49. Electric leads connect the bars 46 and 47 with the magnet 43 as well as with an electric source. When, at the connection of a pair of studs 50, the circuit of the magnet is closed, the armature 40 is attracted and the arm 39 suddenly turned so as to apply the type wheel 36 to the platen. The core 44, which limits the movement of the arm 39, is held by a screw 25 so that it can be adjusted for causing the wheel 36 to make more or less deep impressions in the material 9.

I claim:—

1. In a stereotype-matrix machine, the combination with a carriage, and with a plurality of key-levers, of a plurality of shafts arranged under said key-levers at right angles thereto, a ratchet wheel mounted on one of said shafts for each key-lever, 35 two spring pawls connected to each lever so as to act on the ratchet wheel for turning the latter and the shaft, one pawl being adapted to act when the key is depressed and the other when the lever is restored to 40 normal position, and means for transmitting the movement of the shafts to the carriage for feeding the latter.

2. In a stereotype-matrix machine, the combination with a carriage and a plurality of key-levers, of a plurality of shafts arranged under said key-levers at right angles thereto, a ratchet wheel mounted on one of said shafts for each key-lever, two spring-pawls connected to each lever so as to act 45 on the ratchet-wheel for turning the latter and the shaft, one pawl being adapted to act when the key is depressed and the other when the key is restored to normal position, means for adjusting the pawls so as to turn 50 the wheel through a variable number of tooth spaces, and means for transmitting the

movement of the shafts to the carriage for feeding the latter.

3. In a stereotype-matrix machine, the combination with a carriage and with a plurality of key-levers, of a plurality of shafts arranged under said levers at right angles thereto, a ratchet-wheel mounted on one of said shafts for each lever, two spring-pawls connected to each lever so as to act 65 on the ratchet wheel for turning the latter and the shaft, one pawl being adapted to act when the lever is depressed and the other when the lever is restored to normal position, a rack connected to the carriage, a 70 worm meshing with said rack, and means for transmitting the movement of said shaft to said worm for feeding the carriage.

4. In a stereotype-matrix machine the combination with a carriage and with a plurality of key-levers, of a plurality of shafts arranged under said levers at right angles thereto, a ratchet-wheel mounted on one of said shafts for each key-lever, two 75 spring pawls connected to each lever so as to act on the ratchet wheel for turning the latter and the shaft, one pawl being adapted to act when the wheel is depressed and the other when the wheel is restored to normal 80 position, a rack connected to the carriage, a worm arranged so as to mesh normally with said rack, means for transmitting the movement of said shafts to said worm for feeding the carriage, and means for tripping the worm shaft so as to disengage the 85 worm from the rack for setting the carriage free.

5. In a stereotype-matrix machine, the combination with a type wheel and with a plurality of key-levers, of a spring-actuated operating lever holding said type wheel, an electromagnet, an armature arranged under the magnet and connected to said operating lever so as to turn the latter for applying the wheel to the matrix 100 when it is attracted by the magnet, the core of the magnet being arranged so as to form an abutment for limiting the working stroke of the operating lever, means for varying the position of the core so as to 105 regulate the depth of the impressions, and means for closing the circuit of the magnet when the key is depressed.
